Patented Mar. 17, 1964

197,744

PROJECTION CABINET

Guy Zwahlen, Hialeah, and William S. Bodenhamer,
Miami, Fla., assignors to Zwahlen, Inc., Miami Beach,
Fla., a corporation of Florida

Filed Feb. 13, 1963, Ser. No. 73,579

Term of patent 14 years

(Cl. D61—1)

FIG. 4.FIG. 5.FIG. 6.FIG. 1 is a front perspective view of a projection cabinet in open condition, showing our new design;

FIG. 2 is a rear perspective view thereof;

FIG. 3 is a side perspective view of the cabinet in closed condition;

FIG. 4 is a front elevational view thereof in open condition;

FIG. 5 is a side elevational view thereof; and

FIG. 6 is a side elevational view thereof in closed condition.

We claim:

The ornamental design for a projection cabinet, as shown.
